(57) **CLAIM**

The ornamental design for a ladder talon, as shown and described.

DESCRIPTION

FIG. 1 is a perspective view of a ladder talon, showing my new design;

FIG. 2 is a front view thereof, the rear view being the mirror image thereof;

FIG. 3 is a cross-sectional view taken along the line 3-3 of FIG. 2;

FIG. 4 is a right-side view thereof, the left-side view being the mirror image thereof; and,

FIG. 5 is a top view thereof.

The broken lines depict portions of the article that form no part of the claimed design.
